United States Patent Office

Des. 211,777

Patented July 30, 1968

211,777

HANDLE

Ray C. Bender, P.O. Box 5265,
Pittsburgh, Pa. 15206

Filed Oct. 19, 1966, Ser. No. 4,341

Term of patent 14 years

(Cl. D10—8)

Fig. 1.

Fig. 2.

FIGURE 1 is a side elevation of a handle according to my invention; and

FIGURE 2 is a side elevation of a modified handle according to my invention.

The handle is symmetrical and the side opposite that shown is a mirror image thereof.

I claim:

The ornamental design for a handle, as shown and described.
